UNITED STATES PATENT OFFICE.

EDWIN L. LLOYD, OF PHILADELPHIA, PENNSYLVANIA.

WIRE-HOLDER FOR INSULATORS.

SPECIFICATION forming part of Letters Patent No. 394,380, dated December 11, 1888.

Application filed February 13, 1888. Serial No. 263,777. (No model.)

To all whom it may concern:

Be it known that I, EDWIN L. LLOYD, a citizen of the United States, and a resident of Philadelphia, Pennsylvania, have invented certain 5 Improvements in Wire-Holders for Insulators, of which the following is a specification.

The object of my invention is to so construct a wire-holder for insulators that the 10 stringing of the wire and the tightening of the same from pole to pole can be readily effected, and so that the wire will be firmly retained after its application to the insulator. This object I attain in the manner hereinafter set forth, reference being had to the accompanying drawings, in which—

Figure 1 is a perspective view of an insulator with a wire-holder constructed in accordance with my invention. Fig. 2 is a sectional plan view of the same, with the wire and 20 its holder shown in outside view; and Fig. 3 is a similar view showing another form of the holder.

A represents the glass insulator, of the usual form, having near the top a groove, a, 25 which ordinarily receives the tying-wire, whereby the wire x is confined to the insulator. In place of this tying-wire I use a wire loop, B, having at each end an open eye, b, for the reception of the wire x. In stringing 30 the latter it may simply be passed behind the eyes and drawn tight from pole to pole, the wire being then drawn forward in front of each eye and slipped over the projecting hook d, in which the eye terminates, so that the 35 wire will enter the opposite eyes, and will be retained thereby against displacement in any direction. By the term "open eye," therefore, I mean one into which the wire can be readily slipped without having to be passed 40 through the same endwise, and yet which confines the wire on all sides—that is to say, on top, bottom, front, and rear—so that while the ready application of the wire is permitted, the latter, after having been once applied to the 45 holder, cannot be accidentally dislodged therefrom. My improved holder in this respect, therefore, differs essentially from one which has been proposed, and which consists simply

of a loop with its ends turned back to hold the wire, as the hooks formed by such turning back of the ends of the loop fail to properly retain the wire after it has been applied thereto.

In some cases the loop may have an open eye at one end only, the other end being 55 straight, as in Fig. 3, so that, as shown by full lines in said figure, the holder supports the wire while it is being stretched, after which tension is imparted to the straight end of the loop, and said end is coiled around the wire 60 so as to bring the parts to the condition shown by dotted lines in Fig. 3, thus securely confining the wire to the insulator.

I therefore claim as my invention—

1. The within-described wire-holder for insulators, the same consisting of a loop having a wire-receiving eye open for the insertion of the wire, but having portions extending below, in front of, above, and in rear of a wire passing through the eye, all substantially as 65 70 specified.

2. The combination of the insulator having a groove below the top with the wire and a holder therefor, consisting of a loop contained in the groove of the insulator and 75 having at its ends eyes for retaining the wire, one of said eyes being open for the insertion of the wire, but extending below, in front of, above, and in rear of the wire to confine the same, all substantially as specified. 80

3. The combination of the insulator having a groove below the top, the wire, and the holder therefor, consisting of a loop contained in the groove and having at each end an eye to retain the wire, said eye being open for the 85 insertion of the wire, but extending below, in front of, above, and in rear of the wire, all substantially as specified.

In testimony whereof I have signed my name to this specification in the presence of two sub- 90 scributing witnesses.

EDWIN L. LLOYD.
